UNITED STATES PATENT OFFICE

LAWRENCE S. KORSEN, OF CHICAGO, ILLINOIS

SPOTLIGHT AND THE LIKE

Application filed May 13, 1931. Serial No. 537,154.

This invention has to do with improvements in small spot lights—that is, small electric lamps which are illuminated by a dry battery or the like. The features of the invention herein disclosed have reference particularly to improvements in spot lights of size comparable to that of a lead pencil, so that they can be readily carried in a vest pocket or similar location.

One object is to provide a pencil size spot light which is provided with a clip for engagement with the edge of the pocket so that the spot light will be safely held in place in the pocket and will not become readily lost or displaced.

In this connection, it is an object of the invention to provide a spot light construction in which the clip above referred to constitutes a portion of the electric circuit for controlling the illumination of the light, the clip being normally slightly disengaged from the contact position but capable of being readily forced into the contacting position by a slight pressure exerted on the end of the clip.

In connection with the foregoing, it is an object of the invention to mount the clip in such a manner that it can be turned around the shell to a position in which it will not close the circuit in case the clip should be accidentally depressed. This will insure against improper accidental closing of the circuit with consequent wastage of current and running down the battery.

Another feature in connection with the foregoing is to provide a construction in which the clip is permanently attached to the end socket into which the incandescent lamp is inserted. By so doing, these parts are readily manufactured as a unit.

Another feature of the invention relates to the provisions of a spot light construction including a retaining and enclosing shell for the cells of battery, said shell being formed of a strip of paper which is wrapped directly around the battery cells, thereby enclosing them, providing a housing and mounting for them, and at the same time insulating them. In connection with the foregoing, it is a further object of the invention to provide in some cases a glazed and more permanent fin-

ish for this shell and housing by the provision of a layer or coating of such material as celluloid or the like around the outside thereof. In some cases, this layer or coating is established after the paper wrapper has been wrapped around the battery cells, whereas, in other cases, the glazed or celluloid or other protecting coating may be provided on the surface of the paper before the same is wrapped around the cells.

In connection with the foregoing, it is a further object to provide an arrangement whereby one of the electric conductors necessary for establishing the electrical circuit may be folded and wrapped directly into the paper shell as the same is wrapped around the battery cells. In this connection, it is an object to so arrange the parts that when this conductor has been wrapped into place, it will establish the desired electrical connection at one end and will come into proper position at the other end for electrical contact by the clip button when depressed.

Other objects and uses of the invention will appear from a detailed description of the features of construction and combinations of parts hereinafter described and claimed.

In the drawings

Figure 1 shows a longitudinal section through a device embodying the features of the present invention, the same being shown on enlarged scale;

Figure 2 shows a cross section on the line 2—2 of Figure 1, looking in the direction of the arrows;

Figure 3 shows a view similar to that of Figure 2, but illustrating a construction in which the celluloid or glazed coating is formed directly on the outside face of the paper strip itself; and

Figure 4 shows an inside face view of the paper strip or blank before the same is rolled up, the strip of tinfoil conductor being shown in place.

Referring first to Figure 1, I have therein illustrated two cells of battery 5 and 6, placed end to end. Each of these includes an outer shell constituting one pole or terminal of the battery and a central end contact at one end

which constitutes the other pole. When the two cells are set together end to end as shown in Figure 1, the center contact 7 of the lower cell comes into engagement with the bottom 5 of the outer shell of the upper cell 5, and the central terminal 8 of the upper cell is in position to be engaged by the center contact of the lamp presently to be described.

The two cells 5 and 6 are surrounded and 10 enclosed by an insulating layer 9 of paper or the like, and in some cases an outside layer 10 of celluloid or other water-proof and protecting material is placed around the outside of the device.

15 The paper shell 9 is carried up beyond the upper end of the upper cell 5 a sufficient distance to receive the lamp socket 11. Said lamp socket is generally provided with two or three turns of rather coarse thread as 20 illustrated in Figure 1, and by screwing the lamp socket down into the projecting portion of the paper shell, these threads will work themselves into the material of the paper shell and thus in effect thread the socket 25 into place.

The socket member 11 also includes the downwardly extending neck portion 12, which receives the base 13 of the incandescent lamp 14. When the lamp is thus threaded 30 into place its central contact 15 engages the contact 8 of the cell 5 so as to establish connection therewith.

There is a spring clip 16, the upper end 17 of which is either soldered or brazed or otherwise 35 permanently attached to the flange 18 of the socket member 11. The lower end of the clip 16 is generally provided with a small ball 19 in line with a hole 20 formed in the outside shell of the casing or housing, but said 40 hole 20 does not extend clear through the insulating material or layer 9, but stops short thereof as shown in Figure 1.

A strip of conducting material 21 such as 45 tinfoil or the like, has its lower end in engagement with the outside shell of the lower cell 6. Said strip 21 then extends up along the device to a position opposite to and even beyond the opening 20, it being noticed from examination of Figure 1 that the strip 21 is 50 also insulated from the outside shell of the cell 5. Due to this circumstance there is no short circuiting of the two cells together; and when the clip 16 is depressed so as to carry its ball 19 through the opening 20, said 55 ball makes contact with the conducting strip 21 and thus closes the electric circuit, applying the full voltage to the lamp filament and illuminating the same.

It will be noted that in order to prevent accidental closing of the lamp circuit, the socket member 11 may be turned or unthreaded a slight distance so that the clip 16 is rotated away from a position of coincidence with the opening 20. Under such circumstances, the 65 clip if depressed will not close the circuit.

As a manufacturing proposition, I prefer to build up this spotlight in the following manner;

The insulating or paper layer 9 is cut into the form of a rectangular blank as shown in 70 Figure 4, one corner at the lower end thereof being cut away as shown at 22. The strip of tin foil 21 is then laid along the surface of the blank as shown in Figure 4, with its lower end overlying this cut away portion 22. The blank is also provided with a hole 23 adjacent to its other edge and at the proper position to correspond to the ball 19 of the clip 16. The two cells 5 and 6 are wrapped into the blank 9 commencing at the 75 left hand edge thereof, it being understood that the strip 21 lies to the outside of the blank 9. The blank is then wrapped around the two cells and the blank is of sufficient width to enable it to wrap around approximately one and one-fourth times as shown in 80 Figure 2. Thereupon, the right hand edge portion of the blank will come around and overlie the conducting strip 21, thereby insulating and protecting the same exteriorly. At the same time, the conducting strip 21 is insulated from the outside surfaces of the cells 5 and 6 at all points with the exception of the position of the notch 22, at 85 which point the lower end of the conducting strip 21 will reach over and make direct contact with the outside surface of the lower cell 6. Furthermore, when the paper strip 9 has been wrapped around in the above manner, the hole 23 will come around to a 90 position where it overlies the upper portion of the conducting strip 21 so as to expose the same at a point where the ball 19 of the clip 16 may work through said hole and close 95 the circuit when the clip is depressed. 100

After the paper blank has been wrapped around in the above manner, its edge may be sealed, being gummed or otherwise provided for that purpose; and if desired an outside layer 10 of celluloid or other material may be wrapped in place or formed directly on to the outside surface of the paper strip. Both forms are illustrated in Figures 105 2 and 3. In any case, however, the layer 10 is provided with an opening which will register with the opening 23 so that the proper circuit closing operations may be performed.

Generally a small cap or cup 24 will be placed on the lower end of the device after the paper strip has been wrapped thereon. 110 This cap or cup may be of thin sheet metal, and by dipping the lower end of the assembled device into a solution of celluloid in acetone or something of that kind, the parts 115 will be cemented together.

After the wrapping has been placed on the cells in the above manner, the socket member 11 may be screwed down into the projecting upper end thereof, whereupon the manufacturing operations are complete. 120 125 130

Due to the simplicity of this construction and assemblage, it is possible to manufacture these devices for an extremely low manufacturing cost.

5 While I have herein shown and described only certain features of my present invention, still I do not intend to limit myself thereto except as I may do so in the claims.

I claim:

- 10 1. As an article of manufacture, a spot light comprising in combination a pair of electric cells, each having a central contact of one polarity, and an external shell of opposite polarity, said cells being placed in axial alignment, with the central contact of one cell in engagement with the bottom of the shell of the cell above to establish series contact therewith, a casing for said cells comprising a blank of paper or the like wrapped around the two cells and projecting beyond the upper end of the upper cell, said paper blank, or the like, having one of its lower corners cut away, a strip of conducting material laid against the edge portion of the paper blank at the side away from the cells and having its lower end overlying said cut away portion and in electrical contact with the shell of the lower cell, said paper blank being wrapped around the cells and overlying said strip of conducting material to protect and insulate the same, there being a hole in said overlying portion of the paper blank in alignment with said strip of conducting material, an electric socket threaded into the projecting end portion of the paper shell above the uppermost cell, an electric lamp threaded into said socket and having its central contact in engagement with the central contact of the uppermost cell, and a spring clip secured to said socket member and making electrical contact therewith and extending downwardly at the outside of the shell to a position opposite to the hole aforesaid, whereby upon depression of said spring clip, its lower end projects through the hole aforesaid and into electrical contact with the conducting strip aforesaid to thereby close the circuit, substantially as described.
- 15 2. As a new article of manufacture, a spot light comprising in combination a pair of electric cells of cylindrical form located in cylindrical alignment with each other and in series electrical connection with each other, the outer shell of the lower cell constituting one polarity, there being a central upwardly extending contact on the upper cell constituting the other polarity, a paper blank or the like, wrapped around the two cells to protect them and establish an enclosing shell for them, there being a cut-away portion in the lower portion of said paper blank or the like, a conducting strip laid against the paper blank or the like at the opposite face thereof from the electric cells, the lower end of said conducting strip reaching through said cut
- 20 away portion and into electric contact with the outer shell of the lower cell, the paper blank or the like being wrapped around said conducting strip and provided with an opening in said wrapped around portion in registry with the conducting strip, the paper blank or the like extending beyond the upper end of the upper cell, a socket member seated into said projecting portion, an electric lamp located in said socket member and having a central contact in engagement with the central contact of the upper cell of the series, and a spring clip secured to said socket member and in electrical connection therewith and projecting downwardly along the outside of the device to a position opposite to the hole aforesaid, whereby when said spring clip is depressed, it reaches through said hole and into electrical contact with the conducting strip to thereby close the circuit, substantially as described.
- 25 3. As a new article of manufacture, a spot light comprising in combination an electric battery having an exterior shell establishing one polarity and also having a central upwardly extending contact of opposite polarity, a protecting and insulating shell for said battery comprising a blank of paper or the like wrapped around said battery to enclose and protect the same and said paper blank extending beyond the upper end of the battery, a strip of conducting material laid in axial direction between the convolutions of said blank of paper or the like, the blank aforesaid being suitably formed to permit engagement of said conducting strip with the outer shell of the battery at one point, and being elsewhere insulated therefrom, a socket member inserted into and supported by the projecting portion of the shell of the convolutions of the blank of paper or the like, an electric lamp located within said socket member and having a central contact in engagement with the central contact of the battery, and a spring clip connected to and in electrical contact with said shell, said spring clip overlying the outside of the device to a position in alignment with an opening in the outside convolutions of the paper blank, whereby when the spring clip is depressed, its lower end extends through said opening and into contact with the strip of conducting material aforesaid, substantially as described.
- 30 4. As a new article of manufacture, a spot light comprising in combination an electric battery having an exterior shell establishing one polarity and also having a central upwardly extending contact for opposite polarity, a protecting and insulating shell for said battery enclosing the same, a strip of conducting material laid in axial direction and enclosed within the material of said protecting and insulating shell, the lower end of said strip of conducting material be-

ing in electrical connection with the exterior shell of the battery, there being an opening in the insulating material permitting communication with the strip of conducting material at such point, a socket member supported by the upper portion of the shell, and electric lamp located within said socket member and having a central contact in engagement with the central contact of the battery, and a spring clip connected to and in electrical contact with said shell, said spring clip overlying the outside of the device to a position in alignment with the opening in the insulating material, whereby when the spring clip is depressed, its lower end extends through said openings and into contact with the strip of conducting material aforesaid, substantially as described.

5. As a new article of manufacture a spot light comprising in combination an electric battery having an exterior shell establishing one polarity and also having a central upwardly extending contact of opposite polarity, a protecting and insulating shell for said battery enclosing the same, a strip of conducting material laid in axial direction and enclosed within the material of said protecting and insulating shell, there being an opening in the insulating material permitting communication with the strip of conducting material at such point, a socket member supported by the upper portion of the shell, an electric lamp located within said socket member and having a central contact in engagement with the central contact of the battery, whereby the socket member is of one polarity and the exterior shell of the battery is of opposite polarity, a spring clip in electrical connection with one of said parts, and the strip of conducting material being in electrical connection with the other of said parts, the free end of the spring clip being in alignment with the opening in the insulating shell, whereby when said spring clip is depressed, it makes contact with the conducting strip to close the circuit, substantially as described.
